UNITED STATES PATENT OFFICE

FORREST A. HEATH, OF DETROIT, MICHIGAN

CARBURETOR

Application filed August 17, 1923. Serial No. 657,851.

This invention relates to carburetors and has special reference to that class of carburetors which are devoid of float chambers, floats and such devices which maintain a constant body of fuel as gasoline in proximity to the carburetor. My carburetor also belongs in that class having by-paths for admitting auxiliary supplies of gasoline and air to the intake manifold of an internal combustion engine and my carburetor may be characterized in the following particulars.

First, there is a novel air metering valve provided with a fuel metering pin which is movable in synchronism with the air metering valve and controls the admixture of air and gasoline in the main mixing chamber of the carburetor with the gasoline supply encountering an auxiliary or modulating supply of air in advance of commingling with the main supply of air.

Second, a novel priming valve is articulated with an air choke valve with the priming valve adapted to be opened only during the last few degrees of movement of the choke valve in closing. This permits partial to almost complete closing of the choke valve within the limits employed in various degrees of enriching the explosive mixture for motor operation during "warming-up" or under sub normal motor temperature conditions without opening the priming valve.

Third, there are novel means for breaking up or otherwise disintegrating globules or other small bodies of gasoline which may pass through the mixing chamber without being thoroughly atomized, and these interference elements are located so as to be constantly active for the priming and main supplies of fuel to the motor. In breaking particles of fuel which may be in suspension I place the same in better condition for combustion, obtain a more extensive fuel surface area in a combustion chamber, and consequently provide for a rapid flame propagation.

Fourth, the design of this carburetor permits the elimination of the float mechanism characteristic of the conventional carburetor, which is designed to prevent variation of fuel head acting upon the fuel outlet in the

carburetor, because the fuel-breaking and the fuel and air mixing factors of this carburetor produce constant homogeneity in the mixture created. It has been found that in a homogeneous mixture the fuel content may be widely varied, especially in the direction of diminishment from the percentage approximated in the conventional type of carburetor, without affecting the functioning of the motor. The conventional type of carburetor contains no means of insuring homogeneity in the mixture, the highest degree attained being due to a synchronization of the mixing effects due to the areas and shapes of the passages in the carburetor, the manifold and the intakes of the motor cylinders. With the conventional carburetor, the variation of the fuel head—even to the degree involved through the shaking of the contents of a float chamber in motor vehicle operation over a road surface other than absolutely smooth—causes variation in the fuel content of the mixture which changes the effects produced by the mixing factors entering into the synchronization referred to, and changes in turn the degree of homogeneity in the mixture arriving in the combustion chamber of the motor cylinder. This variation not only changes the average power output of the cylinder explosions through the changing of the average degree of richness of the mixture at the point in the compressed mass where the ignition occurs, but, in the case of a multiple-cylinder motor, changes the average fuel content of the charge delivered to the various cylinders through the similar variation of the degree of homogeneity at the point in the manifold where distribution to the various cylinders occurs.

My carburetor possesses other characteristics that will appear as the invention is more fully described, by aid of the accompanying drawings, wherein:

Figure 1 is a vertical, longitudinal sectional view of the carburetor;

Fig. 2 is a horizontal sectional view taken on the line II—II of Fig. 1;

Fig. 3 is a plan of the carburetor partly broken away;

Fig. 4 is a perspective view of a detached

air metering valve, partly broken away and partly in section;

Fig. 5 is a similar view of a portion of a fuel outlet member of the carburetor;

Fig. 6 is a vertical cross sectional view of a portion of the carburetor, and

Fig. 7 is a side elevation of the carburetor showing the adjusting mechanism between the air choke and priming valves.

The carburetor comprises a body 1 having a mixing chamber 2 and an air chamber 3 separated by a partition 4 provided with a valve seat opening 5 adapted to establish communication between the chambers 2 and 3.

One side of the carburetor body 1 has a warm air intake connection 6 communicating with the air chamber 3 and in this connection is a conventional form of butterfly choke valve 7 carried by a transversely disposed rock shaft 8 having its outer end provided with a crank 9. The air intake connection 6 is also adapted to communicate with the mixing chamber 2 through an upwardly directed auxiliary air by-path 10 in an enlargement 11 of the partition 4 at its juncture with the carburetor body 1. The by-path 10 may be restricted or completely closed by a conventional form of screw valve 12.

The bottom of the carburetor body 1 has an opening 13 and mounted in said opening and suitably secured to the carburetor body 1 is a base piece 14 having a depending stem 15 provided with an axial bore 16. The lower end of the bore 16 is enlarged and its walls interiorly screwthreaded to receive the ported nipple 17 of a fuel inlet connection 18 which is provided with an adjustable needle valve 19 that may be set to regulate the inflow of liquid fuel, as gasoline or kerosene, into the bore 16 of the stem 15. On one side of the stem 15 is an enlargement 20 having an angularly disposed priming by-path 21 communicating with the bore 16 through a part 22 and the passage of fuel from the bore 16 into the by-path 21 is controlled by a screw valve 23 movable to and from the port 22. On the outer end of the screw valve 23 is a crank 24 having a screw and slot connection 25 with a link 26 pivotally connected, as at 27, to the crank 9 of the choke valve 7. The manner of articulating the choke valve 7 and the screw valve 23 is such that the screw valve is only open during the final closing movement of the choke valve, thus leaving said valve free for adjustment within the limits employed for controlling the main intake of air to the carburetor.

The inner wall of the air chamber 3 has an enlargement provided with a by-path 28 establishing communication between the by-path 21 and the mixing chamber 2, at a point above the opening 5, so that when this opening is closed priming fuel may enter the

mixing chamber 2 for priming purposes as will hereinafter appear.

Alining with the stem 15 of the base piece 14 and extending upwardly through the air chamber 3 into the opening 5 is a fuel inlet member or stud 29 having its walls longitudinally fluted, as at 30 and the lower ends of the flutes terminating at a shoulder 31. Axially of the fuel outlet member 29 is a bore 32 communicating with the bore 16 through a tapered or restricted portion 33 affording a valve seat 34. Above the seat 34 are radially disposed and outwardly flared fuel outlet orifices 35 opening into the flutes 30 of the fuel outlet member 29.

Slidable on the fuel outlet member 29 is an air metering valve 36 adapted to close the opening 5 of the partition 4 and said air metering valve has an apertured top wall 37 with its apertures 38 disposed to communicate with a plurality of air passages formed by the flutes 30 of the fuel outlet member co-operating with the inner annular wall 39 of the air metering valve 36. This air metering valve is adapted to be automatically raised or unseated by reduction of atmospheric pressure in the mixing chamber 2 produced by the reciprocable pistons in a multi-cylinder internal combustion engine. The valve is adapted to close by gravity and to limit the sliding movement of said valve on the fuel outlet member 29 the base piece 14 is provided with horizontally disposed yoke shaped abutments 40 and 41 adapted to be engaged by a peripheral flange 42 on the lower end of the air metering valve 36.

Extending into the bore 32 of the fuel outlet member 29 is a metering pin or fuel controlling valve that may be integral with the air metering valve 36 or loosely suspended axially of said valve from the perforated top wall 37 thereof. The metering pin or valve 43 extends into the tapered portion 33 of the bore 32 and is adapted to engage the seat 34 and close the bore 16 relative to the bore 32 or the fuel outlet orifices 35.

The top of the carburetor body 1 has a manifold connection 45 communicating with the mixing chamber 2 and provided with the usual flanges 46 by which the carburetor can be readily connected to the intake manifold of an internal combustion engine. In the manifold connection 45 is a conventional form of butterfly throttle 47 adapted to be adjusted in the usual manner to control the supply of an explosive mixture to the cylinders of an engine, and in the manifold connection, above the throttle 47, is an interference member comprising a sleeve 48, a swirling fin 49 and superposed screens or baffles 50. The sleeve 48 is suitably fixed in the manifold connection 45 and the swirling fin 49 is in the form of a spiral convolute to impart a swirling action to the mixture which impinges against said fin, and the screens 50

are of a foraminous construction, made of woven wire or the like, and are adapted to cooperate with the fin 49 in breaking up any large particles of gasoline or kerosene which escape atomization in the lower part of the carburetor. Large particles of fuel will impinge against the screens and spread thereon as films to be attacked by air and thoroughly atomized.

10 Considering the operation of the carburetor, the air in volume determined by position of butterfly throttle 47 enters through warm air connections 6, raises the air metering valve 36 until the opening 5 is of sufficient area to accommodate said volume, less the amount 15 of air entering modulating passages 30 at the shoulder 31 and entering by-path 10 governed by idle adjustment valve 12 and reaches main mixing chamber 2.

20 Fuel, in volume determined by position of fuel metering valve 43 (which in turn is determined by the extent of rise of air metering valve 36), in the tapered fuel bore or passage 33, enters at fuel supply member 18 which is carried by the stem 15, passes 25 through radial fuel orifices 35 where it is carried by air through passages 30 to a primary mixing chamber 51 in the top of the valve 36 and through apertures 38, and reaches main 30 mixing chamber 2 impinging upon the outer edge of the disk head 52 of the fuel metering pin 43.

The diverging annular spray of fuel and air joins the annular column of air in the main mixing chamber 2, passes by the butterfly throttle 47, and this mixture in a state already approximating homogeneity is given a rotary motion by impact against the swirling fin 42, and then passes through the interference member 48 at the angle of spiral rotation against which the fuel particles are more thoroughly broken and homogeneously diffused through the air medium.

For starting a cold motor, especially in 45 very low temperatures, the ordinary procedure of closing the choke valve 7 opens the primer screw valve 23 through the primer actuating mechanism 24 and 26 which is connected with the choke shaft 8. This primer 50 actuating mechanism is of such a nature that the primer valve 23 is opened only during the last few degrees of movement of the choke shaft 8 in closing the choke. This permits partial to almost complete closing of the 55 choke valve 7, in other words, free use of the choke valve within the limits employed in the various degrees of enriching of the mixture for motor operation during the "warming up" period or under sub-normal motor 60 temperature conditions—without opening the primer valve 23. When the primer valve 23 is opened fuel flows through the primer by-paths 21 and 28; and the throttle 47 being open to a greater degree than the choke 65 valve 7, the vacuum of the motor cylinder is

communicated to the primer by-path outlet located just above the air valve opening 5, thereby securing the emission of a small stream of fuel at high velocity. This stream of fuel, subjected to the influence of the swirl-and-interference member, is shattered into fine particles susceptible to conveyance in the air column through cold manifold and inlet passages to the motor, in suspension, which not only insures the arrival of fuel in the combustion chamber of the motor, but in a condition involving such extensive fuel surface area as to produce instant combustion and comparatively rapid flame propagation.

If the fuel be supplied under head, the abutment 40 is used only in the case of the metering pin 43 carried by, but not integral with, the air valve 36. If the fuel be supplied by suction, under sub-head, the abutment 40 may be used with air and fuel valves integral. The abutment 40 has the double function of determining the location of the air valve 36 at rest and of silencing its action in dropping to point of rest. In the case of valves being integral, the first function of the abutment 40 would be performed by the fuel metering pin seat 34, because when the air valve 36 is at rest the metering pin 43 must be seated to shut off the flow of fuel that would otherwise continue under head pressure. The abutment 41 has the double function of limiting the rise of the air metering valve 36 to the maximum air requirements of the motor and of silencing its action when thus limited. In the case of fuel drawn from a point below the level of the carburetor the air valve 36 and metering pin 43 may be integral and may rest on the abutment 41 because the necessity no longer exists of shutting off a fuel flow.

In the case of fuel supplied from a point below the carburetor, the carburetor is changed in no way except that the air valve 36 is given sufficient weight to set up the required amount of sub-atmospheric pressure in the main mixing chamber 2 necessary to lift the fuel the required distance.

Considering the motor idling adjustment, the areas of the annular passage between the air valve 36 and its seat, and of the annular passage between the fuel metering pin and the walls of the tapered seat 34, are known quantities. Adequate tolerance in the production of parts involves slight variations in these annular passages. The function of the idle adjustment is to compensate for these variations, and further to make such variations of the known quantities as may be required by variations in the compression of the motor, whether created by design or deterioration, or variations in the volatility of the fuel or the density of the air. This basic condition being determined, the rise of the air and fuel metering valves causes the an-

nular passages to be increased along straight lines maintaining the relationship established in the calibration of the metering mechanism, from minimum air and fuel at 5 idling motor speed up to maximum air accommodated by the motor cylinders or determined by the abutment 41 and maximum fuel determined by the limiting action of the maximum fuel valve 19.

10 What I claim is:—

In a carburetor, a fuel outlet member having lateral outlet orifices, an adjustable air metering valve having an apertured top piece, said air valve spacedly surrounding 15 said fuel outlet member and orifices and affording an annular air passage open at its lower end to permit of air in said passage sweeping past and removing fuel from the lateral outlet orifices of said member and 20 carrying the fuel to a primary mixing chamber formed by the upper end of said fuel outlet member and said top piece of said air metering valve, a metering pin extending into said fuel outlet member and controlling the 25 outlet of fuel from the lateral orifices of said member and means for limiting the opening and closing movement of said air metering valve.

30 In testimony whereof I affix my signature.
